UNITED STATES PATENT OFFICE.

HARRY W. CODDINGTON, OF ROANOKE, VIRGINIA.

FLANGE-LUBRICATOR.

1,073,093.

Specification of Letters Patent. Patented Sept. 16, 1913.

Application filed September 21, 1912. Serial No. 721,562.

To all whom it may concern:

Be it known that I, HARRY W. CODDINGTON, a citizen of the United States, residing at Roanoke, in the county of Roanoke and 5 State of Virginia, have invented certain new and useful Improvements in Flange-Lubricators, of which the following is a specification.

The object of my invention is to provide 10 means for properly lubricating the flanges of wheels of railway vehicles, or the sides of the rails against which they bear.

With this object in view, my invention consists in the combination and arrangement of parts as will be more fully herein-after described, and particularly pointed out in the appended claims.

In the drawings, Figure 1, is a side elevation of an ordinary locomotive with my device applied. Fig. 2 is an end view showing the position of the discharge nozzle in its relation to the flange of a wheel. Fig. 3 is a detail view of the discharge nozzle of my invention.

Referring to the drawings, in which like parts are given the same reference numbers wherever they occur, 1 represents a locomotive, 2 the driving wheels for same. At some accessible point preferably within the cab 30 of the locomotive I locate an oil tank or reservoir 3. This reservoir may be of any shape or design, it being simply an oil retainer and never being subject to pressure. The reservoir shown is provided with a 35 loose lid 4, and a strainer 5, but these are not necessarily a part of my invention. From the bottom of oil reservoir 3 I lead off one oil pipe 6 for each flange or other point to be lubricated. In this oil pipe 40 is placed a needle valve 7 for regulating the feed of oil from the reservoir and a sight feed glass 8 for observing the same.

From some convenient point I bring a steam pipe 9, and by a suitable connection 45 10 I pass the oil pipe 6 through the inside of the steam pipe 9. This is done so that steam being fed through the pipe 9 for a purpose herein-after stated will keep the oil warm in its passage through the pipe 6, and 50 hence allow it to flow freely in cold weather as well as in warmer weather.

At 11 the oil pipe 6 and the steam pipe 9 are again separated by any suitable connection and from thence they pass separately to a discharge nozzle 12 which is so 55 constructed that steam entering at 13 and

discharging through a series of internal nozzles 14 and 15 produces a partial vacuum in the chamber 16 thereby adding to the head due to the oil above to cause the oil to flow down the pipe 6 and into the discharge nozzle 12 at 17, where it is drawn into the current of steam and discharged through the internal nozzle 15.

The discharge nozzle 12 is of course located so that the oil and steam are discharged upon the surface to be lubricated, as at 23.

For convenience in operating I provide the several following appurtenances.

18 is a valve in the steam pipe 9 for closing off the steam supply when the locomotive is stopped for any considerable length of time.

19 is a permanent contraction of the steam pipe so that it will not be possible for the attendant to allow too much steam to escape through the discharge nozzle 12, thereby obstructing the view of the engineer.

At 20 is a steam connection directly to the oil pipe 6 with a valve 21 to control this steam supply and a valve 22 in the oil pipe 6 just above the steam connection 20. By closing valve 22 and opening valve 21, steam is forced through the oil pipe 6 to blow out 85 any dirt or other stoppage. In service, valve 22 is open and valve 21 closed.

Having thus described my invention, what I claim as new, and desire to secure by Letters Patent, is:

1. In a lubricator for the flanges of the wheels of railway vehicles the combination of an oil reservoir, an oil pipe leading therefrom, a steam pipe surrounding said oil pipe, an oil ejector consisting of a series of internal nozzles with a surrounding shell adapted to receive the said oil and steam pipes at separate points, and an additional steam pipe leading to said oil pipe, adapted to deliver steam through the oil pipe for blowing out same, substantially as described.

2. In a lubricator for the flanges of the wheels of railway vehicles the combination of a reservoir for oil at atmospheric pressure, an oil pipe leading from the bottom thereof, a steam pipe surrounding said oil pipe for the major portion of its length, said steam and oil pipes terminating separately in an oil ejector consisting of an outer shell with a series of internal nozzles and being adapted to deliver the oil and steam against the flange to be lubricated, and means for

forcing steam through the oil pipe for cleaning, substantially as described.

3. In a lubricator for the flanges of the wheels of railway vehicles, the combination of a reservoir for oil at atmospheric pressure, an oil pipe leading from the bottom thereof, a steam pipe surrounding said oil pipe for the major portion of its length, said steam and oil pipes terminating in an oil ejector consisting of an outer shell with a series of internal nozzles and being adapted to deliver the oil and steam against the flange to be lubricated, and means for forcing steam through the oil pipe for cleaning, substantially as described.
4. In a lubricator for the flanges of the wheels of railway vehicles the combination of a reservoir for oil at atmospheric pres-

sure, an oil pipe leading from the bottom thereof, a needle valve and a sight feed 20 glass in said oil pipe, a steam pipe surrounding said oil pipe for the major portion of its length, means for separating the said oil and steam pipes, an oil ejector comprising an outer shell and two internal nozzles 25 adapted to deliver the oil and steam against the flange to be lubricated, and means for connecting said oil and steam pipes to the ejector body, substantially as described.

In testimony whereof I affix my signature 30 in presence of two witnesses.

HARRY W. CODDINGTON.
